SECTIONAL SHIELD DEVICE

John Kosinski, New Hyde Park, N. Y.

Application July 24, 1947, Serial No. 763,268

3 Claims. (Cl. 211—119.18)

1

This invention relates to sectional cover or shield device for a clothesline, and more particularly to a sectional shield, whereon the clothes are supported and which is adapted to travel section by section along the conventional clothesline or cable as a support and guide.

In windy weather, clothes tend to become twisted around a clothesline, thus fouling the line and making the removal of the clothes more difficult. This is particularly true where a double line and pulley arrangement is employed.

The principal object of this invention is to reduce fouling of the clothesline.

Another object is to facilitate the removal of fouled articles from a clothesline.

In the drawings comprising two sheets of eight figures, numbered Figs. 1 to 8, inclusive, one suggested embodiment of the invention and its mode of practice is shown.

Fig. 1 is a front view of a clothesline showing the sectional shield devices, with the clothesline and one of the shield devices partially broken away;

Fig. 2 is a plan view of two of the sectional shield devices partially broken away;

Fig. 3 is a side view thereof;

Fig. 4 is an enlarged fragmentary view of the coupling members partially in cross-section;

Fig. 5 is a vertical cross-sectional view taken along the line 5—5 of Fig. 3, looking in the direction of the arrows;

Fig. 6 is a plan view showing how the sectional shield devices are applied to a pulley-actuated double clothesline;

Fig. 7 is a fragmentary view showing a portion of one of the shields in vertical cross-section; and

Fig. 8 is a horizontal cross-section taken along the line 8—8 of Fig. 7, looking in the direction of the arrows.

Like reference characters designate corresponding parts throughout the several figures of the drawings.

Referring generally to Figs. 1 to 4, the conventional clothesline 20 may be supported in any conventional manner as between the posts 21 and 22. The clothesline 20 may be detachably attached to the hooks 23 and 24 which are anchored to the posts 21 and 22, the line 20 being detachably secured to the hooks 23 and 24 in any suitable way as by means of the eyelets 25 and 26.

At the post 22, the clothesline 20 is made readily accessible to the operator, or the hook 24 may be anchored to the wall of the building adjacent

2

the door or window from which point the wet wash is hung.

Instead of attaching the wet wash to the clothesline 20 with clothespins in the conventional manner, the operator first attaches the detachable shields 27, 28, 29, 30, etc., in succession upon the clothesline 20 and attaches the wash to the detachable shields 27, etc. in succession, by means of the conventional clothespins.

The detachable shields 27 are attached to the clothesline 20 one at a time and the first piece of the wet wash which is to be hung out is secured to the detachable shield 27 by means of the conventional clothespin, and section 27 is then pushed along the clothesline 20 away from the operator until sufficient clearance is provided to attach the next detachable shield 28 to the shield 27 and to the clothesline 20.

The next article of wet wash to be hung out is then attached to the shield 28 by means of the conventional clothespins and section 28 carrying the wet wash and carrying detachable shield 27 before it, is then pushed along the clothesline 20 until sufficient room is provided between section 28 and the operator to furnish access for the detachable shield 29 which is then hooked to the detachable shield 28 and to the clothesline 20 and the operation is repeated until the last detachable shield, which may be the shield 30, is coupled to the detachable shield 29 and to the clothesline to receive another article of wet wash clamped thereon by the conventional clothespin.

Each detachable shield, 27 to 30, etc. is constructed in the same manner. As best shown in Figs. 2 to 5, each detachable shield is made of a piece of material of suitable length for the purpose intended. A piece of material, approximately twelve inches long, gives good results although it should be understood that the detachable shields may be longer or shorter than twelve inches without in any way departing from the spirit of the invention.

Each shield 27, includes an elongated cover substantially conforming in cross-section to an inverted U. The cover is wide enough and deep enough in cross-section to accommodate and encase a section of the conventional clothesline 20. At its opposite ends, and at one or more intermediate points, the detachable shield 27 is provided with pairs of oppositely disposed clips 32—33, 34—35, 36—37.

As best illustrated in Fig. 5, each of the clips is inwardly bent to engage a portion of the underside of the clothesline 20, and is then outwardly bent to form the oppositely disposed flared lips

38 and 39 between which a section of clothesline 20 may be readily inserted.

The detachable shields 27 may be made of any suitable material which is rust-proof and which will not stain or soil the wet wash and which is sufficiently self-resilient to spring open and closed about the clothesline, when attached thereto and detached therefrom. Sheet brass gives satisfactory results although other metals and even plastic materials may be substituted for brass, if desired.

At suitably spaced intervals, detents 40, 41 and 42 may be formed in the crown of the inverted U-shaped cover 31 to provide spacers 44, 45 and 46 having smooth-curved undersurfaces along which the crown of the clothesline 20 may slide freely. By this arrangement, friction between the clothesline 20 and the detachable shields 27 to 30, etc., is reduced to a minimum, thus facilitating the movement of the detachable shields along the clothesline.

The side walls of the U-shaped cover 31 may be struck outwards to provide the outwardly projecting beads or ridges 48 and 49, which in conjunction with the clothespins tend to firmly secure the end of the pinned article between the clothespin and the cover 31 and to prevent premature release of the clothespin from the shield.

One end of the cover 31 is struck upwards and outwards at 50 to form a raised shank having an elongated curved slot 51 formed therein, and the opposite end of the cover 31 terminates in a laterally and upwardly projecting end piece defining a hook 55. As best shown in Fig. 4, the elongated curved slot 52 of detachable shield 28, is adapted to engage the hook 55 of detachable shield 27 whereby the hook 55 and elongated curved slot 52 constitute a detachable coupling between the adjacent detachable shields 27 and 28, so that when the shields 27 and 28 are attached to the clothesline in succession, and are coupled together by means of slot 52, and hook 55, the detachable shields 27 and 28 may be moved by the operator as a unit and caused to glide along the clothesline towards or away from the operator by the action of the curved spacers 44, 45, 46, 47, etc., and the clamping action of the clips 32-33, 34-35, 36-37, etc.

In the modified form shown in Figs. 6 to 8 inclusive, a double or endless clothesline 60 is suspended as between the posts 61 and 62 by means of the hooks 63 and 64 and the pulley assemblies 65 and 66.

Each pulley assembly 65 and 66 is conventional and may consist of an eyelet 67 pivoted at 68 to the case of the pulley assembly 65 (Figs. 7 and 8), and a grooved pulley 69 mounted to revolve about a fixed shaft 70. The case of the pulley assembly 65 may include the spaced guide channels 71 and 72 through which the clothesline 60 may be guided around the grooved pulley 69.

The wet wash shown generally at 73, may be attached with clothespins 74 to the outward run 78 of clothesline 60 in the conventional way, and the inward run 79 drawn towards the operator at 61 until the knot 80 reaches the guide channel of pulley 66 (Fig. 1) when the outward run 78 of the clothesline 60 will be filled with wet wash 73.

The operator may now proceed to attach successive sections of the detachable shields 29, 28, 27 to the inward run 79 of clothesline 60 and attach wet wash to said shields 29, 28, etc.

in succession, until the inward run 79 is filled with wet wash in the manner described for the clothesline 20 (Fig. 1). The stop washers 76 and 75 prevent the detachable shields 27, 28, 29, etc., from entering the guide channels 71 and 72 of the pulley assemblies 66 and 65. The stop washers 75, 76 are provided with a central opening 77 through which the clothesline 60 may run freely when drawn by the operator.

10 The wet wash may whip and spread before the wind, but the detachable shields 27, 28, 29 tend to turn upon the clothesline 20 thus reducing the risk of fouling of the wet wash about the clothesline 20. However, if the wet wash should 15 foul up around the detachable shields 27, 28, 29, the shields may still be drawn along the clothesline towards the operator and the wet wash removed as the shields 27, 28, 29, etc., are drawn in. The stop washers 75 and 76 engage the guide 20 channel 72 of the pulley assembly to prevent the detachable shields 27, 28, 29, etc., disposed on clothesline 60 between said stop washers, from fouling in the guide channels 71, 72 of the pulley assembly 65.

25 Instead of pinning the wet wash to the shields 29, 28, 27, etc., of the double clothesline shown in Fig. 6, the operator may attach the wet wash 73 with the clothespins 74 to the outward run 78 and merely fasten the shields 29, 28, 27, etc., 30 to the inward run 79, and leave them in place as a permanent part of the clothesline structure.

The outward run 78, may be operated through the pulley assemblies 65 and 66 in the conventional way to hang and remove the wet wash 73.

35 When, however, any article of wet wash becomes tangled with or wrapped around the detachable shields 29, 28, 27, of the inward run 79, the operator may draw the outward run 78 towards the post 61 while at the same time drawing the 40 innermost shield 27 towards the post 61, so that the article which is tangled with the shield travels freely upon both the outward run 78 and the inward run 79 until it is accessible to the operator who then disentangles the article and detaches it from the clothesline.

45 What is claimed is:

1. A sectional shield device comprising, a clothesline, a series of shields attachable to said clothesline, each of said shields comprising an elongated member having the cross-section of an inverted U and adapted to slidably engage the clothesline to form a shield, oppositely spaced spring clips in continuation of the lower edges of said shield for detachably clamping said shield upon said clothesline, and coupling means disposed at opposite ends of said shield.

2. A sectional shield device for a cable comprising a series of shields attachable to a cable, each of said shields including a flexible elongated member having the cross-section of an inverted U adapted to cover a definite length of a suspended cable, oppositely spaced spring clips extending below the lower edges of said elongated member for detachably clamping said member upon said cable, a hook secured to one end of said shield, the opposite end thereof having an eye formed therein, and detents formed in the crown of said shield in spaced alignment to form rolling surfaces for the suspended cable.

3. A sectional shield device for a cable comprising a series of shields attachable to a cable, each of said shields including a flexible elongated member having the cross-section of an inverted U adapted to cover a definite length of

a suspended cable, oppositely spaced spring clips extending below the lower edges of said elongated member for detachably clamping said member upon said cable, a hook secured to one end of said shield, the opposite end thereof having an eye formed therein, detents formed in the crown of said shield in spaced alignment to form rolling surfaces for the suspended cable, and beads extending along the side walls of the shield.
